UNITED STATES PATENT OFFICE.

EDWARD H. KRUSE, OF FORT WAYNE, INDIANA.

MOUNTING-STRIP FOR SWITCH-BOXES.

1,211,182.

Specification of Letters Patent. Patented Jan. 2, 1917.

Application filed February 17, 1916. Serial No. 78,845.

To all whom it may concern:

Be it known that I, EDWARD H. KRUSE, a citizen of the United States of America, and resident of Fort Wayne, in the county of 5 Allen and State of Indiana, have invented certain new and useful Improvements in Mounting-Strips for Switch-Boxes, of which the following is a specification.

This invention relates to improvements in 10 mounting strips for switch-boxes, and is intended particularly for holding in place boxes of that type ordinarily installed in buildings for containing electrical switches.

The objects of the invention are to provide 15 strips constructed so as to be readily and permanently positioned by the use of ordinary nails, and also to so form the strips as to facilitate the attachment of the box or boxes in connection with the strips, as well 20 as to hold the boxes in the intended position.

The objects of the invention are accomplished by the construction illustrated in the accompanying drawings in which:

Figure 1 is an elevation showing a switch-25 box mounted in a pair of strips embodying the invention, the strips being positioned on the studding of a building; Fig. 2 is a perspective view showing a portion of one of the strips, viewed from the back; and Fig. 30 3 is a detail view showing a portion of Fig. 1 on the line $\alpha-\alpha$ thereof.

Similar characters of reference indicate corresponding parts throughout the several views and referring now to the same: (A) is 35 a metallic supporting strip, the margins of which are folded so as to extend in parallel planes and with an intervening space (B) therebetween. The front portion (C) of the strip has a bead (D) formed along its edge, 40 and the rear portion (E) extends somewhat beyond the edge of the front portion and has made therein a series of bosses (F) that project from its front face toward the front portion. These bosses are made in the strip 45 by depressing the corresponding parts of the back thereof. A series of holes (G) is made in the strip, the holes being in opposite pairs, there being holes in both portions thereof. The strips are made of convenient 50 lengths so as to be fastened readily with their ends attached respectively to corre-

sponding studs (H), and the holes (G) are so spaced apart that by shifting the strip horizontally a pair of holes may be brought into alignment with each of the studs so that 55 nails (A') may be driven through the holes into the studs and thereby secure the strip in place. It is the intention to secure the strips to the studs in pairs with their open sides toward each other so that the brackets 60 (J) that extend from the top and bottom of the switch-box (K) may extend into the strips correspondingly. The brackets are held snugly between the folded sides of the strip, and the bosses project respectively 65 into the voids (L) of the brackets, thus holding the boxes from becoming displaced.

In using the invention a switch-box is secured to one of the strips and the strip is then positioned on the studding so that the 70 box is brought to the desired position, the strip being then securely nailed. Should a number of other boxes be required, as in forming a group, they may be secured to the strip by inserting their brackets at one end 75 into the strip. The protruding edge of the back portion (E) facilitates the insertion of the brackets as it serves as a guide for directing the end of the bracket into the space (B). When the boxes have been ar- 80 ranged in connection with the nailed strip, another strip is then placed in connection with the brackets at the opposite ends of the boxes and when so secured the latter strip is also nailed to the studding. 85

What I claim is:-

1. A mounting strip consisting of a folded metallic plate, the folded portions being spaced apart, the back portion extending beyond the edge of the front portion there- 90 of, the front portion having a bead formed therein along its edge, and the back portion having a series of bosses that project toward the front portion, said strip having holes made therein that extend through both por- 95 tions.

2. A mounting strip consisting of a folded metallic plate, the folded portions being spaced apart, the back portion extending above the edge of the front portion thereof, 100 the front portion having a bead formed therein along its edge.

3. A mounting strip consisting of a folded metallic plate, the folded portions being spaced apart, and the back portion having made therein forwardly protruding bosses.
- 5 4. A mounting strip consisting of a folded plate the front and back portions being parallel to each other, the front part having a bead made therein along its upper edge, and the back part being straight, its upper

edge extending above the plane of the front 10 part.

In testimony whereof I affix my signature, in presence of two witnesses.

EDWARD H. KRUSE.
